Primary Examiner — Phillip S Hyder(74) *Attorney, Agent, or Firm* — Hogan Lovells US LLP(57) **CLAIM**

The ornamental design for a proppant vessel, as shown and described.

DESCRIPTION

FIG. 1 is an upper perspective view of the proppant vessel showing our [design] design;

FIG. 2 is a front elevation view thereof;

FIG. 3 is a rear elevation view thereof;

FIG. 4 is a right side elevation view thereof;

FIG. 5 is [an opposite] a left side elevation view thereof;

FIG. 6 is a top plan view thereof; and,

FIG. 7 is a bottom plan view thereof.

The broken lines depict portions of the proppant vessel in which the design is embodied that are not considered part of the claimed design.

1 Claim, 2 Drawing Sheets

Matter enclosed in heavy brackets [ ] appears in the original patent but forms no part of this reissue; matter printed in italics indicates the additions made by reissue.
